HERVEY WATERS, OF NORTHBIDGE, MASSACHUSETTS.

Letters Patent No. 60,973, dated January 1, 1867.

IMPROVED MECHANISM FOR OPERATING DIES.

The Schedule referred to in these Letters Patent and making part of the same.

TO ALL WHOM IT MAY CONCERN:

Be it known that I, HERVEY WATERS, of Northbridge, county of Worcester, and State of Massachusetts, have invented an improvement in Working Presses, etc.; and I do hereby declare that the following, taken in connection with the drawings which accompany and form part of this specification, is a description of my invention, sufficient to enable those skilled in the art to practise it.

The specific object of my invention is to work with facility and accuracy certain devices used in my improved method of manufacturing scythes, it being employed by me, first, as an adjunct to a crank-press used in stamping the heels of scythes when at a red heat, so as to operate the stamp with accuracy, and without injury thereunto; second, as an adjunct to my finishing presses, so as to be able to work them with facility and accuracy. Generally the invention may be employed for any and every purpose to which the contrivance is adapted, the common crank-hammer being among the various others.

Previous to the date of my invention, the common eccentric hammer, among other ways, had been organized as follows, viz; the connecting-rod had been detached in so far as to allow it to work forward without carrying forward the die, but so as always to bring back the die after the die was thrown forward, (or the die being brought back by a spring or weight,) the die or die-slide being provided with a suitable shoulder to receive the end of the connecting-rod upon it, and the end of the connecting-rod being jointed to a lever, the connection could, by the lever, be made or broken at pleasure so far as throwing forward the die was concerned, the die always drawing back with the connecting-rod. This arrangement, however, although very well for some purposes, is not adapted to others, particularly where it is desirable to give a single blow at pleasure upon hot work, for, if the eccentric be run slowly, so as to enable the operator to make and break the connection for a single blow, the die holds on to the work too long, and, if the eccentric runs quickly, it will be found difficult for the operator to make but a single blow at pleasure. My invention consists of a peculiar mechanism, having the character of an adjunct, or appurtenance to an eccentric hammer, or other machine or machines, so as to enable an attendant to work said machine or machines according to a rule fixed and determined by the appurtenance, said appurtenance being connected with the machine, one or more, but not entering into the active laboring structure thereof, the peculiarity of operation being, that notwithstanding the actuating mechanism of the machine moves with great rapidity, the operating device is entirely at the control of the attendant, but according to the fixed rule of the appurtenance. When used as an adjunct to the eccentric hammer, constructed and arranged in the manner before described, it is peculiarly adapted to obviate the difficulties there referred to, and is then organized as follows, viz: Upon the eccentric shaft is fixed a cam or wiper; this cam actuates a lever, which has a jointed attachment to the end of the pitman or connecting-rod, so that when the lever is permitted to work down upon the cam, by means of a spring or weight, it will, as it descends, bring the end of the pitman upon the shoulder of the die, and carry it forward, (the cam being in proper relation to the eccentric for that purpose,) and the die will thus be brought to its work, the cam or wiper being duly formed to act upon the lever, so that after the blow is struck, it will, by positive action, take off the pitman from the shoulder and return it to its normal position. Now this lever, at its extreme backward movement, is caught by a spring-hook, and held there so that it cannot go down the second time; but this spring-hook is furnished with a bolt or latch, and the cam is furnished with another cam upon it, or moving in conjunction with it, to the action of which the latch or bolt may be brought by the operator, so as to have the secondary cam unhook the lever, and thus again get the blow when wanted. The bolt or latch is brought into position by a catch, so arranged that it, the catch, shall be disengaged at substantially the same time the hook is, and this bolt or latch, being always forced toward its normal position by a spring, will, when the catch is disengaged, move instantly out of the track of the secondary cam, and the hook, being pressed towards its normal position by a spring, will be quite sure to catch up the lever at its extreme backward movement, and thus hold the connection broken between the connecting-rod and the die so far as any forward movement is concerned. It will be observed that this adjunct to the eccentric hammer is somewhat complex, but it will also be observed that none of this complexity enters into the arrangement by which the labor of the blow is performed. All that remains substantially as before, the attendant, by means of the new device, indicating when the work shall be done, but that limiting it to a single blow. If, however, more than one, and less than any given number of blows be desired, it will be seen that, by

slight changes, any desired number may be determined, as will fully appear in certain applications for patents which I intend to make, as soon as practicable, for my improvements in apparatus for the manufacture of scythes, hereinbefore referred to.

For a better understanding of this appurtenance, reference may be had to Figures 1, 2, and 3, on sheet 1 of the drawings annexed to this specification, which figures show respectively, a front view, a side elevation, and a vertical section of an eccentric hammer, having my invention embodied therewith; and to Figure 4, which is a fragmentary view of part of the adjunct mechanism.

a is the main-frame of the machine; *b* the driving pulley, which serves as a fly; *c* the eccentric shaft; *d* the connecting-rod; *e* the slide for the die. The lower die should be attached to the main frame, and made adjustable in all directions; and through the connecting-rod is a mortise, through which extends a hook from the die-slide, so as always to bring back the die at each backward movement of the connecting-rod. *g* is the main cam, and *h* an auxiliary cam fixed upon it, and turning uniformly with it. *i* is an arm or lever, actuated by the main cam, and made fast upon a shaft, *j*. Upon the same shaft are made fast the arms *k*, having their outer ends connected to the outer end of the connecting-rod *d*. On the shaft *j* may be seen an arm, furnished with a stout spring, *l*. *m* is a strut, having a shoulder or catch near its upper end, upon which the arm *i* rests by the force of the spring *l*. The lower end of the strut is jointed to the frame *a* of the machine, and furnished with a spring, *n*, which bears it upward to its position under *i*. Connecting with *m*, so as to swing with it, is an arm, extending upward so that a sliding bolt, *o*, may pass through it and through the strut, and have in each a bearing in which it can slide freely. This bolt is furnished with a stop-collar, made fast upon it, and between the stop-collar and the strut is a spiral spring, bearing the collar up against the arm. *q* is a bent lever, having its fulcrum at *p*, a handle, *t*, forming one arm, and upon the other arm, within a mortise, is jointed the latch *r*, furnished with a spring, *u*, (see fig. 4,) made fast upon *q*, which bears it up against a stop on *q*. This lever is furnished with a spring and stop to maintain it in its normal position when not acted upon by the hand of the operator, but to get a blow, the operator depresses the handle *t*, thus bringing the latch *r* against the bolt *o*, and thrusting it forward so as to be impinged upon by the auxiliary cam *h*, which will swing out the strut *m*, removing its shoulder from under *i*, which, by the power of the spring *l*, will be made to follow down upon the cam *g*. The arm *k*, through its connections, will bring the outer end of the connecting-rod upon the shoulder of the slide *e*, when (by the revolution of the eccentric) the slide, with the die, will be carried down by the shoulder upon its work, giving the blow desired. In the continuation of the revolution, the connecting-rod draws back the slide by the hooked arm, while the cam *g* raises up the lever *i* to its normal position, when the strut *m* will, by the power of the spring *n*, be returned to its normal position, because that notwithstanding the operator shall still continue to keep the lever depressed, the bolt *o* will escape from the latch at the same time, or immediately after the time, that the shoulder upon *m* is clear of the lever *i*, and the spiral spring upon the bolt *o* will return it to its normal position; and the spring *n* will return the catch to its normal position, as before described, overcoming the power of the lighter spring, *u*, by the pressure of the bolt upon the latch *r*. When the operator takes his hand from the handle *t*, the lever will be returned to its normal position, clearing the latch from the bolt, and the latch will be returned to its normal position by the power of the spring *u*. In some cases it may be best to modify the eccentric hammer by an arrangement as follows: The end of the connecting-rod is made to work back and forth in a right line, directly over the shoulder of the die-slide, but shorter than will quite reach it when it is drawn back by the hooked arm, and the connection from the arm *k*, instead of taking hold of the connecting-rod, taking hold of a chock of suitable size and form, (and fitted to work upon the die-slide,) so as to get the blow when desired by introducing it between the end of the connecting-rod and the shoulder of the die-slide.

What I claim is the combination, with an eccentric hammer, crank-press, or other similarly operating machine or machines, of a means or system of mechanism, by which the action of the machine or machines may be controlled, substantially as set forth, when such system of mechanism is so connected with the machine or machines as not to enter into the active operating structure thereof.

In witness whereof I have hereunto set my hand this eleventh day of October, A. D. one thousand eight hundred and sixty-four.

HERVEY WATERS.
